UNITED STATES PATENT OFFICE.

HENRY L. TIFFANY, OF SOUTH DARTMOUTH, MASSACHUSETTS.

CONE-TUBE.

1,240,103.

Specification of Letters Patent. Patented Sept. 11, 1917.

Application filed March 25, 1915. Serial No. 17,034.

To all whom it may concern:

Be it known that I, HENRY L. TIFFANY, a citizen of the United States, and a resident of South Dartmouth, in the county of 5 Bristol and State of Massachusetts, have invented an Improvement in Cone Tubes, of which the following description, in connection with the accompanying drawings, is a specification, like characters on the drawings 10 representing like parts.

This invention relates to cone tubes adapted to receive or have wound thereon yarn, thread or the like of the commonly known cone winding form and from which the yarn 15 is drawn off axially or substantially so.

In certain aspects thereof, my invention is an improvement upon that shown in the patent to Charles Gess, No. 986,379, dated March 7, 1911.

20 In order that the principle of the invention may be readily understood, I have disclosed a single embodiment thereof in the accompanying drawing, wherein—

Figure 1 is a side elevation of a cone tube 25 embodying my invention;

Fig. 2 is a vertical, central section thereof;

Fig. 3 is a plan view of the tube shown in Fig. 1;

Fig. 4 is a cross sectional view thereof;

30 Fig. 5 is a sectional view of the tip end of the tube; and

Fig. 6 is a plan view of the blank from which the cone tube is wound.

Cone tubes adapted to receive or have 35 yarn or thread wound thereon and from which said yarn or thread is drawn off axially when in upright position are customarily formed of paper rolled in one or more layers or coils into conical form.

40 These tubes are adapted to be mounted for winding upon tapering arbors of the general shape of the tubes and extending through said tube to within an inch or two of the tip end thereof. The ends of these conical

45 tubes generally protrude somewhat from the complete yarn or thread mass. A cone tube of this general character but having an in-turned apex end is disclosed in said Gess Patent No. 986,379, and I have represented 50 the disclosed embodiment of my invention as applied thereto.

Referring more particularly to the drawings and to the single embodiment of the invention here illustrated, the blank from 55 which the cone or tube is formed is represented at 1 in Fig. 6, it being preferably of

the segmental shape there shown. The said blank is coiled as indicated in Fig. 4 into a suitable number of contacting layers and the inner edges of the said layers should for the best results terminate substantially flush 60 with each other, as indicated at 2 in Fig. 5.

Owing to the fact that the conical tubes are markedly tapering to facilitate the unwinding of the yarn or thread (such tapering materially exceeding that of the usual spinning spindle), it is exceedingly important in effecting the best results that such cone tubes be superficially roughened, thus preventing the slipping or displacement of 70

the yarn or thread as the first series of layers thereof are wound upon the tube and subsequently. This tendency to displacement, particularly of the first laid layers, exists to a marked degree in a cone having 75

a decided taper, but it is nevertheless of importance that the cone tube and the yarn package wound thereon be of decided or markedly tapering form. Such roughening may be of any suitable character, though 80

preferably it is effected by providing the cone tube with longitudinal ridges 3 inclined from top to bottom, such roughening being effected either prior or subsequently to the coiling of the paper or other material 85

into tube form, but preferably while the material is in its flat form. If as prepared the cone tube be superficially roughened, the roughened portion is removed from the tip portion of the tube which, as stated, should 90

present no obstruction to the unwinding of the yarn or thread and especially to the unwinding of the first laid layers thereof.

In order to prevent the first laid coils or layers of the yarn or thread from contacting with the tip end of the cone tube as they are unwound therefrom, the tip end 5 thereof is inturned or upset in any suitable manner, as represented most clearly in Figs. 1, 2 and 5. The tip end of the cone tube 100 should, for effecting the best results, be very materially inturned and preferably so as substantially, if not wholly, to close said tip end, and the inturned end may be turned into the cone tube to any desired extent so 105 as to provide a downwardly extending edge portion.

The tip end of the cone tube, as yarn or thread is being wound thereon, projects very materially beyond the tapered end of the 110 supporting arbor. The approximate position of the outer end of the arbor is indi-

cated by the dotted line $x-x$ in Fig. 2, and is therefore free from contact with the said tip end of the cone tube. It is therefore possible to upset or inturn the tip end of 5 the cone to a very marked degree and so as effectively to prevent the breaking or chafing of the yarn or thread by said tip end as the yarn or thread is unwound.

The cone is markedly conical in order to 10 permit the yarn to free itself from the roughened surface when drawn from the end of the cone and is provided with stiff, cone supporting, side walls to sustain the usually large and heavy package. The tip end of 15 the cone preferably is not only inturned but is smooth, the roughened surface of the body of the cone blending into the smooth, inturned surface of the tip. The said inturned tip end is preferably indifferently 20 centered internally with respect to the axis of the cone, this being possible because the tip end of the cone extends beyond the driver. This is a matter of practical importance, inasmuch as if, in manufacturing 25 the cone, the apex end thereof be somewhat warped or distorted, the fact that the tip end extends beyond the driver permits it to conform in position substantially to the driver, whereby the yarn or thread as drawn 30 off will not be obstructed or impaired by said warped or deflected portion.

In accordance with my invention, I suitably reinforce the tip portion of the tube and this I preferably effect by treating it 35 with some suitable material, such, for example, as sizing, as indicated by the heavier section lines 6 in Fig. 2. Inasmuch as the tip portions of the cone tubes protrude somewhat from the formed packages, such tip 40 ends are liable to become crushed or somewhat damaged during transportation. An important object of my invention is to overcome this defect which preferably I accomplish by treating the tip end. So far as I 45 am aware, I am the first to treat the tip end of a cone tube for this purpose, and I shall therefore claim the same broadly whether the tip end be inturned or not, but in its preferred embodiment I contemplate the in- 50 turning of the tip end of the cone tube, such inturned tip end being sized or otherwise suitably treated at any suitable time, but for reasons hereinafter set forth being preferably treated subsequent to the inturning. 55 Such treated tip end of the cone tube is preferably subsequently polished, so that said cone tube in its preferred embodiment has an inturned, treated, polished end which not only presents no obstruction to the un- 60 winding of the layers of yarn or thread, but cannot readily be crushed or damaged in transportation. The sizing or treatment of the tip end may extend downward to any suitable point.

65 The inturning of the tip end of the tube

may be effected in any suitable manner or by any suitable means not herein necessary particularly to disclose. In effecting the inturning of the tip end of the tube, the material of such tip may be somewhat twisted 70 or circumferentially displaced, as indicated at 7 in Figs. 1 and 3.

When the cone tube is in its normal condition,—that is, before the tip end thereof has been inturned,—such tip end is substantially 75 unyielding to inward pressure. When, however, the material of the tube has been circumferentially displaced, then the arch effect existing prior to inturning is materially lost and the twisted portions of the edge, because 80 of their displacement, will more readily yield inwardly. This inturning may be satisfactorily effected by subjecting the unturned end to the action of a die, the die and cone tube having a movement of relative 85 rotation. Such relative rotation of the cone tube and die coincidently softens the material of the tip end portion, thus enabling it to be turned inwardly and to lay snugly in the die and to receive the smooth, highly de- 90 sirable, polished surface. Such softening of the tip end renders such tip end less stiff and lacking in rigidity than the body of the tube, it being therefore more pliable and yielding than the body thereof. This, how- 95 ever, renders the tip end liable to be crushed or damaged in transportation and to over- come this I treat the tip end as heretofore set forth and preferably by subjecting it to the action of some suitable material, such, 100 for example, as sizing, by means of which such softening or yielding character is offset or neutralized. In adapting my invention therefore to a cone tube having an inturned end, I preferably apply the stiffening ma- 105 terial thereto after the inturning thereof has been effected, thus neutralizing, partially or wholly, the softening action incident to the inturning of such tip end.

The sizing or other material is preferably 110 so applied to the inturned end and subsequent to the inturning action that it neutralizes the softening of the end created by or incident to the inturning action, and therefore the finished cone tube with its 115 inturned treated end is of substantially uniform stiffness throughout. This result has never heretofore been accomplished so far as I am aware. The sizing or other material may be applied in such excess as to result in 120 making the tip end of the cone tube stronger than the body thereof.

I have found in practice that if the in- turned end be superficially polished and smooth, it will not offer such resistance to 125 the yarn or thread as to chafe or break the latter, even though such inturned end be reinforced or stiffened by subjecting it to the action of sizing or other suitable material.

The cone tube is preferably formed from 130

a segmental sheet of paper pulp, papier mâché or other fibrous material coiled upon itself into a plurality of coils or turns.

Having thus described one illustrative embodiment of my invention, I desire it to be understood that although specific terms are employed, they are used in a generic and descriptive sense and not for purposes of limitation, the scope of the invention being set forth in the following claims.

Claims:

1. As an article of manufacture, a winding cone having a yarn-retaining surface markedly conical in shape, and provided with an inturned apex end treated with a reinforcing material incorporated into the substance of the cone.

2. As an article of manufacture, a winding cone having a yarn-retaining surface markedly conical in shape, and provided with an inturned apex end reinforced by sizing.

3. As an article of manufacture, a winding cone having a yarn-retaining surface markedly conical in shape and provided with an inturned apex end, said end only being treated with sizing and thereby rendered of substantially uniform stiffness with the body of the cone.

4. As an article of manufacture, a winding cone having a yarn-retaining surface markedly conical in shape and provided with an inturned apex end, treated with stiffening material and superficially polished.

5. As an article of manufacture, a winding cone having a yarn-retaining surface markedly conical in shape and provided with an inturned apex end, sized and thereafter superficially polished.

6. As an article of manufacture, a winding cone having a roughened yarn-retaining surface markedly conical in shape to permit the yarn to free itself from said roughened surface when drawn from the end of said cone, the latter having an inturned apex end treated with sizing to neutralize the softening caused by the inturning action.

7. As an article of manufacture, a winding cone having a roughened yarn-retaining surface markedly conical in shape to permit

the yarn to free itself from said roughened surface when drawn from the end of said cone, the latter having an inturned apex end treated to neutralize the softening caused by the inturning action and superficially polished.

8. As an article of manufacture, a winding cone having a yarn-retaining surface markedly conical in shape, and provided with an inturned apex end treated with a reinforcing material incorporated into the substance of the cone, the material of said end being circumferentially displaced.

9. As an article of manufacture, a winding cone having a yarn-retaining surface markedly conical in shape, and provided with an inturned apex end reinforced by sizing, the material of said end being circumferentially displaced.

10. As an article of manufacture, a winding cone having a roughened, yarn retaining surface markedly conical in shape to permit the yarn to free itself from said roughened surface when drawn from the end of said cone, the tip of the latter being inturned and thereby weakened and softened, said tip end being subsequently reinforced to neutralize the softening caused by the inturning action, thereby rendering the cone tube substantially uniform stiffness throughout.

11. As an article of manufacture, a winding cone having a roughened, yarn retaining surface markedly conical in shape to permit the yarn to free itself from said roughened surface when drawn from the end of said cone, the tip of the latter being inturned and thereby weakened and softened, said tip end subsequent to said inturning being treated with sizing to neutralize the softening and weakening incident to the inturning action, whereby the entire cone is rendered of substantially uniform stiffness throughout.

In testimony whereof, I have signed my name to this specification, in the presence of two subscribing witnesses.

HENRY L. TIFFANY.
